(57) **CLAIM**

The ornamental design for the watch dial, as shown and
described.

DESCRIPTION

FIG. 1 is a front view of a watch dial with a transitional
moonphase and a movable tide indicator showing my new
design, illustrated in a first configuration;

FIG. 2 is a front view of the watch dial illustrated in a second
configuration;

FIG. 3 is a front view of the watch dial illustrated in a third
configuration;

FIG. 4 is a front view of the watch dial illustrated in a fourth
configuration;

FIG. 5 is a front view of the watch dial illustrated in a fifth
configuration;

FIG. 6 is a front view of the watch dial illustrated in a sixth
configuration; and,

FIG. 7 is a front view of the watch dial illustrated in a
seventh configuration and corresponding to the first
configuration.

The broken lines in the drawing figures illustrate an outer
perimeter of the watch dial and form no part of the claimed
design.

The solid black areas in the drawing figures are intended to
show areas of color contrast.
